CONTROL MECHANISM FOR REVOLVING SCRAPERS

Filed Feb. 12, 1927.

INVENTOR
D.R. Throop
BY *Henry J. D. Throop*
ATTORNEY

UNITED STATES PATENT OFFICE.

DAMON R. THROOP, OF STOCKTON, CALIFORNIA.

CONTROL MECHANISM FOR REVOLVING SCRAPERS.

Application filed February 12, 1927. Serial No. 167,662.

This invention relates to improvements in control mechanisms for scraper bowls of the rotary type and particularly represents modifications of the control arrangement shown 5 in my United States Letters Patent No. 1,621,646, dated March 22nd, 1927.

In the previous apparatus the rotation of the bowl was controlled by means of a spider or arm member pivoted on the main control 10 lever, the spider normally engaging a stop on the bowl as well as a stop on the frame which held the spider and consequently the bowl from rotation. To release the spider from the frame stop necessitated raising the 15 lever a certain distance.

The principal object of the present invention is to arrange the stop for the spider in such a manner that it not only allows of the 20 fullest possible range of movement of the main lever without danger of releasing the stop, thus permitting the bowl to be tilted to a number of different positions without being actually released; but enables the release of the bowl when desired to be accomplished more conveniently than before, as 25 no actual raising of the bowl itself has to take place before the stop is released. Also the new control means for the stop can be more conveniently operated when the scraper 30 is being drawn by a tractor, as is usually the case.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

40 In the drawings similar characters of reference indicate corresponding parts in the several views:

Fig. 1 is a side elevation of my improved construction.

Fig. 2 is a top plan view of the same.

Fig. 3 is a fragmentary cross section on the line 3—3 of Fig. 1 showing the particular arrangement of one unit of the control mechanism.

50 Referring now more particularly to the characters of reference on the drawings, the numeral 1 denotes a pair of suitable side frames which converge toward their forward ends and are provided at such end with a clevis 2 for attaching and supporting the frame from a tractor or similar draft means.

Pivotedly mounted on trunnions 3 journaled on the frames adjacent their rear ends is a bowl 4 substantially of the well known Fresno type and resting on the ground. 60 This bowl has runners 5 projecting upwardly from the sides thereof as is customary.

Pivoted onto the frame ahead of the trunnions 3 is a lever unit comprising side arms 6 converging toward each other ahead of the bowl to unite with a single longitudinally extending bar 7. This bar has a pull-mechanism 8 of common character mounted thereon which cooperates with a quadrant 9 70 fixed on the forward portion of the frame structure.

Pivoted on the arms 6 adjacent and outwardly of the front of the bowl are spiders 10. Each spider is preferably the same as 75 is shown in the previous application, having a plurality of arms radiating from a common center. Fixed on each runner 5 and projecting laterally and outwardly therefrom in concentric relation with the 80 trunnions 3 are stop pins 11 which project into the path of rotation of the arms of the spider; one pin normally bearing against the upper face of one of the arms rearwardly of its pivot. Rotation of the spiders is normally prevented by means of other pins 12, each of which bears against the upper face of the other spider arm ahead of the pivot of said spider. These pins are fixed on and project laterally from vertical control arms 90 or levers 13 which are pivotally mounted below the pins on brackets 14 depending from the lever arms 6. The arms 13 are connected at their upper ends by a cross member 15 to which a forwardly extending pull cord 95 16 is attached. It will therefore be seen that the tilting of the bowl from a scraping to a carrying position will be positively controlled by raising or lowering the main lever unit. When it is desired to dump the load and cause the bucket to upset it is only necessary to pull the cord 16 from ahead. This moves the pins 12 forwardly until they clear the spider arms with which said pins previously engaged. This allows the spiders to 100 rotate and with the forward movement of the bowl the pins 11 can rotate the spider until they clear each other. The arms 13 are returned to their normal positions when the pull on the cord is released by suitably connected springs as shown at 17.

From the foregoing description it will be

readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A scraper comprising a frame, a bowl pivoted thereon and resting on the ground, a pin projecting laterally from the bowl in offset relation to the pivot thereof, a lever member pivoted on the frame, arms fixed relative to each other radiating from a common center and pivoted on the lever, one of said arms being disposed to be engaged by the pin, a stop member mounted in connection with the lever to engage the other arm, and means for withdrawing the stop clear of said arm at will.

2. A scraper comprising a frame, a bowl pivoted thereon and resting on the ground, a pin projecting laterally from the bowl in offset relation to the pivot thereof, a lever member pivoted on the frame, arms fixed relative to each other radiating from a common center and pivoted on the lever, one of said arms being disposed to be engaged by the pin, another lever pivoted onto the first named lever, and a stop projecting laterally from said other lever to be engaged by the other arm, and means for moving said other lever; the latter being arranged relative to the arm to cause such movement to draw the stop clear of the path of movement of said arm.

3. A scraper comprising a frame, a bowl

pivoted thereon and resting on the ground, a pin projecting laterally from the bowl in offset relation to the pivot thereof, a lever member pivoted on the frame, arms fixed relative to each other radiating from a common center and pivoted on the lever, one of said arms being disposed to be engaged by the pin, another lever pivoted onto the first named lever, and projecting substantially at right angles to an edge face of the other arm, a stop projecting laterally from said other lever to overhang and be engaged by said arm-face, and means for moving said other lever to move the stop lengthwise of and clear of said arm.

4. A scraper comprising a frame, a bowl pivoted thereon, a pin projecting laterally from the bowl in offset relation to the pivot thereof, a lever pivoted on the frame, a releasable stop member carried by the lever and an instrumentality carried by the lever and normally engaged by the pin and the stop to keep the bowl from being rotated.

5. A structure as in claim 4, and means whereby when the stop is withdrawn from engagement with such instrumentality the same will move clear of the pin and allow the bowl to be rotated.

6. A scraper comprising a frame, a bowl pivoted thereon, a pin projecting laterally from the bowl in offset relation to the pivot thereof, a lever pivoted on the frame, a releasable stop member carried by the lever, unitary arms mounted on the lever and engaging the stop and pin respectively, means to release the stop from engagement with one arm, and means whereby the other arm will then move clear of the pin to allow the bowl to be rotated.

In testimony whereof I affix my signature.

DAMON R. THROOP.
